[57] CLAIM

The ornamental design for a time out display, as shown and described.

DESCRIPTION

FIG. 1 is a front elevational view of the time out display of the present invention;

FIG. 2 is a rear elevational view of the time out display of FIG. 1;

FIG. 3 is a left side elevational view of the time out display of FIG. 1;

FIG. 4 is a right side elevational view of the time out display of FIG. 1; and

FIG. 5 is a top plan view of the time out display of FIG. 1; and,

FIG. 6 is a bottom plan view of the time out display of FIG. 1.

The broken lines showing of numbers inside rectangles in FIGS. 1 and 2 are for illustrative purposes only and form no part of the claimed design.
